UNITED STATES PATENT OFFICE

JOSEPH F. LYNCH, OF STOCKTON, CALIFORNIA

DIRECTION SIGNAL FOR AUTOMOBILES

Application filed December 27, 1926. Serial No. 157,111.

This invention relates to improvements in direction signal devices for motor vehicles to take the place of the hand signals now commonly used. The invention also represents developments of and improvements over the movable type of signal shown in my Patents No. 1,357,504, granted November 2, 1920, and No. 1,470,236, granted October 9, 1923. The principal object of my invention is to provide signal devices arranged to be mounted both at the front and the rear of the vehicle and to provide suction actuated and manually controlled means for enabling both signals to be turned simultaneously from neutral position to point either right or left at the option of the driver.

A further object is to provide a lighting system for the signals so arranged that the lights will be automatically lit whenever the signals are turned one way or the other, but only at night when such lights are necessary; and for enabling the same lights to be used for stop signalling purposes at any time regardless of the turning of the signals.

25 A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claim.

In the drawings similar characters of reference indicate corresponding parts in the several views:

Fig. 1 is a plan outline of a motor vehicle showing my signal arrangement installed thereon in diagrammatic form.

Fig. 2 is a perspective elevation of one of the signal members detached.

Fig. 3 is a sectional elevation of a signal member.

Fig. 4 is a vertical section on the line 4—4 of Fig. 3.

45 Fig. 5 is a top plan view of a suction control valve.

Fig. 6 is a vertical section of the valve on the line 6—6 of Fig. 5.

Fig. 7 is a top plan view of the body of the 50 valve with the rotor removed.

Fig. 8 is a bottom plan view of the valve rotor.

Referring now more particularly to the characters of reference on the drawings, I preferably employ two signal units A, one to be installed in a suitable location at the front end of a vehicle centrally thereof, and the other at the rear end of the vehicle centrally thereof. Each unit comprises a rigid vertical casing 1 rigidly mounted on a bracket 2 of suitable character and shape such as may be readily attached to a vehicle in the desired positions as above stated.

Turnably mounted in the casing near the top is a horizontal and longitudinally extending tubular shaft 3 having on one end outside the casing a socket 4 to receive the sleeve 5 on which the turnable signal element is mounted, the sleeve being fixed in the socket. This signal element comprises a lamp housing 6 fixed centrally on the sleeve 5 and having a convex curvature in a plane longitudinally of the shaft so as to serve as a reflector, but its outer periphery being of rectangular and relatively narrow form. The 70 sleeve 5 at its end inside the lamp housing forms a support for an electric light bulb 7 of ordinary form, and at the other end supports a wire terminal plug 8 contacting with the base of the bulb. The outer rectangular 75 face of the lamp housing is covered by a metal plate 9 cut out intermediate its ends to form an arrow 10 or the like, the plate being backed by a pane of translucent and preferably red colored material 11. The lamp housing is 80 made so that it normally remains balanced with its major axis extending vertically as shown in Fig. 2, and so that it can turn with equal facility one way or the other about the shaft 3 as an axis.

85 Mounted on the shaft 3 inside the casing 1 is a pinion 12 engaged by a vertical rack bar 13. The rack is connected to a piston rod 14 which projects into a vertical cylinder 15 mounted in the casing, the rod having a piston 16 inside the cylinder. These parts are so arranged that when the housing 6 is positioned vertically as above stated, the rack engages the pinion substantially centrally of its length, and the piston is located in the 90

95

100

cylinder centrally of its limits of travel. With the movement of the piston to such limit of travel in either direction the signal member will be turned one way or the other through a 90 degree arc, so that it will be placed in a horizontal position, with the point of the arrow facing either to right or left. It will therefore be evident that if a positive or negative pressure is applied to either end of the cylinder to act on the piston therein, the signal member will be moved as above stated.

To thus actuate the piston I utilize the suctional force constantly had with the operation of the engine of the vehicle in the following manner:

A hollow valve body 17 is provided with a clamping bracket 18 of suitable character so as to enable the body to be attached to the steering column of the vehicle. Turnable in the top of the body is a stem 19 connected to an operating handle 20 of suitable length, which is limited in its turning movement by stops 21 and held centrally between the stops 25 by a spring 22. The inner end of the stem has opposed lugs 23 which engage notches cut in the top rim 24 of the rotor disc 25. The under face of the disc rests on the bottom of the body chamber and is held with a constant pressure thereagainst by a spring 26 between the stem and disc. The adjacent faces of the disc and valve chamber have a central depression 27, that in the disc having diametrically opposed grooves 27^a leading outwardly therefrom. Leading from the bottom of the body to the central depression thereof is a passage 28, while leading from the body to the bottom of the valve chamber outwardly of the central depression are other passages 29 and 30. These passages are arranged in symmetrically opposed and circumferentially offset relation. The outer ends of both passages 29 are adapted to be connected by flexible tubes 31 to a pipe 32 leading to the bottom of the cylinders of the two signal units, while the passages 30 are adapted to be similarly connected by tubes 33 to the pipes 34 leading to the top of the cylinders of the signal units. A tube 35 leads from the central passage 28 to the vacuum tank 36 of the motor vehicle, or to a similar member normally containing a negative or suctional pressure. The disc 25 is so disposed relative to the stem and handle that when the latter is in a neutral or normal position between the stops 21, the grooves 27^a are centrally disposed between the adjacent passages 29 and 30. When the handle is turned one way or the other the grooves will register with either the opposed passages 29 or 30 respectively. It will therefore be seen that when the handle is thus turned, and the engine of the vehicle is operating, communication will be established between the passage 28 and either the passages 29 or 30 to the top or bottom of the

signal cylinders. The suction will cause the piston to be drawn up or down and a corresponding movement of the signals will be had. When such suctional communication is established the other set of passages 29 or 30 are placed in communication with the atmosphere by holes 37 through the disc 25, the body of the valve above the disc not being air-tight.

The lighting system I employ in connection with the signals is as follows:

Fixed on the shaft 3 inside the housing is an insulation collar 38, to which a wire 39 from the plug 8 extends, a contact member 40 to which the wire is connected projecting outwardly from the collar. This contact when the signal is in a neutral vertical position engages a flexible strip 41 connected to a binding post 42. A wire 43 leads from the binding post to the battery 44 of the car, with a suitable manually operated switch 45 interposed therein so that the circuit may be closed at will. It will be understood that, as is usual in automotive practice, a one wire circuit is used, the battery and lamp housing 90 being grounded on the metal of the car. It will therefore be seen that at the option of the driver the lights in the signal units may be lit at will and at any time, to give a desired signal without moving said units.

Normally disengaged from the contact 40 is a contact strip 46, insulated from the strip 41 and having its own binding post 47 insulated from the binding post 42. This contact strip 46 is of such a shape that when the signal is turned one way or the other the contact will be broken between the member 40 and the strip 41, and established between said contact and the strip 46. A wire 48 from the binding post 47 is connected to the tail-light circuit 49 of the car, so that a current will only pass to the signal circuit, even though the signals are turned, at night when the tail-light circuit switch 50 is closed.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claim.

Having thus described my invention what I claim as new and useful and desire to secure by Letters Patent is:

In a direction signal, a lamp housing, an open-ended sleeve projecting through the housing and secured intermediate its ends thereto, a rotatable hollow shaft axially aligned with the sleeve outwardly of the housing, said shaft being of smaller diameter than the sleeve, a socket on the end of the shaft adjacent the sleeve and into which the portion

of the sleeve outwardly of the housing projects, a terminal plug in the sleeve abutted against the adjacent end of the shaft; the sleeve being also arranged to receive the base of a lamp-bulb from its ends inside the housing so that said base will engage the plug and a circuit wire in the shaft leading to the plug.

In testimony whereof I affix my signature.

JOSEPH F. LYNCH.
